UNITED STATES PATENT OFFICE

JOSEPH F. COX, OF BOSTON, MASSACHUSETTS

DROP HAMMER

Application filed August 12, 1929. Serial No. 385,109.

This invention relates to that portion of a drop hammer which includes a bottom die adapted to cooperate with a weighted top die which is alternately raised and released to drop upon work resting on the lower die, the top die being guided in a predetermined vertical path, and the bottom die being adjustable to enable it to accurately register with the top die.

10 The bottom die is supported by a fixed shoe forming a part of the hammer frame. It is essential that the bottom die be longitudinally adjustable on the shoe, toward and from the operator's station.

15 The invention is embodied in improved means, as hereinafter described and claimed, for longitudinally adjusting the bottom die and for positively securing the bottom die in any position to which it is longitudinally 20 adjustable, the invention being an improvement on that disclosed by my Patent No. 1,356,908, dated October 26, 1920.

Of the accompanying drawings forming a part of this specification,—

25 Figure 1 is a fragmentary front elevation showing a portion of a drop-hammer embodying the invention.

Figure 2 is a section on line 2—2 of Figure 1.

30 Figure 3 is a fragmentary transverse section, showing portions of the shoe and the bottom die, and means for engaging the adjusting bar hereinafter described with the bottom die.

35 Figure 4 is a fragmentary section on line 4—4 of Figure 3.

Figure 5 is a perspective view of the adjusting bar.

Figure 5a is a perspective view of a cap.

40 Figure 6 is a fragmentary perspective view, showing the outer end portion of the adjusting bar without its screw.

Figure 7 is a perspective view of the screw.

45 Figure 8 is a view similar to Figure 2, the bracket being attached to the base.

The same reference characters indicate the same parts in all of the figures.

50 Figure 1 of the drawings shows portions of the frame of a drop hammer, said portions including a base 12 and uprights 13 between

which the weighted gravitating upper die, not shown, is guided in a predetermined path.

14 designates the shoe which is mounted on the base 12, in accordance with the usual 55 practice.

16 designates the bottom die which is engaged with the shoe in such manner that the die is adjustable longitudinally, or toward and from the operator's station, the shoe and die being provided with means for permitting a longitudinal adjustment of the die and preventing a lateral adjustment independent of the shoe.

The bottom die 16 has a dovetail projection 17 on its bottom movable in a dovetail recess in the top of the shoe to permit longitudinal adjustments of the die. One longitudinal wall or edge of said recess is formed by an undercut face 18, and is supplemented as 60 usual, by a key or gib 19, formed in cross section, as shown by Figures 1 and 3, and having the usual wedge shape or taper from end to end. I have not illustrated the wedge shape, because the same is well known.

75 The opposite longitudinal wall or edge of the shoe recess is formed by a fixed undercut face 20. Said recess includes a flat bottom face between the undercut faces 18 and 20. The face 20 in accordance with my invention, 80 is supplemented by an elongated member shown separately by Figure 5. Said member includes a base portion 21 slidable in a guiding groove 22 (Figure 3) in the shoe, and a gib portion 23, having an inclined face conforming to the undercut recess face 20, and an undercut face engaging one edge of the dovetail projection 17 of the lower die. Between the ends of said member is a tenon 26, entering a socket 27 (Figure 4) in the bottom die, 85 so that an endwise movement of the member causes an endwise movement of the die.

90 On the outer end of the adjusting bar is a downwardly projecting ear 28, to which is fixed an adjusting screw 29, extending parallel with the bar.

An angular bracket 30 is fixed by bolts 31 to the outer end of the shoe, and has an 95 standing abutment portion provided with an opening 32 (Figure 2) through which the 100

screw 29 extends. With the screw is engaged a pair of clamping nuts 33, adapted to be set up against abutments formed by opposite sides of the upstanding portion of the bracket. Provision is thus made for positively securing the adjusting bar and the die 16 engaged therewith, in any position to which they may be adjusted, there being no liability of accidental loosening and endwise movement of the bar.

It will be seen that the member shown by Figure 5 has a dual function, in that it adjusts the die and aids in guiding it in a predetermined path, the gib portion 23 constituting an element of die-guiding means.

To provide a rigid separable connection between the screw 29 and the ear 28, I provide the screw with a head or enlargement including a threaded portion 35, engaged with a tapped orifice 36 in the ear, and a shouldered hexagonal wrench-engaging portion 37, seated on the outer side of the ear, and bracing the screw. In case the screw is disabled, it can be readily removed and another substituted for it.

It will be seen that the means for adjusting the elongated member is wholly below the path in which the lower die is movable, so that said die may project to any desired extent from the forward end of the shoe.

The tenon 26 is integral both with the base portion 21 and the gib portion 23, so that it is firmly supported by the adjusting bar.

In case the socket 27 in the die is wider than the tenon, the latter may be enlarged by a thin sheet metal cap 40, shown by Figure 5a placed on the tenon.

Means such as a lock nut 33a may be provided for preventing accidental rotation of the outer nut 33. The inner nut 33 is held so firmly against the inner side of the abutment portion of the bracket 30, by the outer screw and the locking nut 33a that it is not liable to be accidentally rotated.

A bushing 41 of compressible material such as lead or fiber, may be inserted in the orifice 32, the screw 29 passing through said bushing. The object of the bushing is to prevent the transmission of jars or vibrations from the bracket 30 to the screw 29, and thus prevent crystallization of the screw.

When the shoe 14 is of minimum thickness, the bracket 30 may be attached to the base 12, as shown by Figure 8.

I claim:

1. A drop hammer comprising a fixed shoe, having in its upper side a longitudinally extending recess defined by spaced apart undercut edge faces 18 and 20, and an intermediate bottom face in which a guiding groove 22 is formed, an elongated member including a base portion slidable in said groove and a gib portion having an inclined outer side face conforming to the undercut recess face 20 and an undercut inner side face overhang-

ing the recess bottom, a gib 19 having an inclined outer side face conforming to the undercut recess face 18, and an undercut inner side face overhanging the recess bottom, said gibs and recess bottom defining a dovetail guideway, a bottom die having a dovetail projection on its under side interengaged with and movable in said guideway, said elongated member having a tenon engaging a socket in said dovetail projection to cause longitudinal movements of the member to longitudinally adjust the die, and means for longitudinally adjusting said member and positively securing it in any position to which it may be adjusted.

2. A drop hammer comprising a fixed shoe, having in its upper side a longitudinally extending recess defined by spaced apart undercut edge faces 18 and 20, and an intermediate bottom face, in which a guiding groove 22 is formed, an elongated member including a base portion slidable in said groove and a gib portion having an inclined outer side face conforming to the undercut recess face 20, and an undercut inner side face overhanging the recess bottom, a gib 19 having an inclined outer side face conforming to the undercut recess face 18 and an undercut inner side face overhanging the recess bottom, said gibs and recess bottom defining a dovetail guideway, a bottom die having a dovetail projection on its under side interengaged with and movable in said guideway, said elongated member having a tenon engaging a socket in said dovetail projection to cause longitudinal movements of the member to longitudinally adjust the die, said member having a downwardly projecting ear at its outer end, an adjusting screw having an enlarged screw threaded head engaged with a tapped socket in said ear, a fixed bracket having an orifice through which said screw extends, and nuts engaged with the screw at opposite sides of the abutment and adapted to lock the screw to the abutment in various adjusted positions.

3. A drop hammer as specified by claim 2, said bracket having an orifice through which the adjusting screw extends, and a compressible bushing interposed between the screw and the wall of the orifice to prevent crystallization of the screw by jars or vibrations.

In testimony whereof I have affixed my signature.

JOSEPH F. COX.
